No. 839,276.

PATENTED DEC. 25, 1906.

J. R. DREW.
ADJUSTABLE EXTENSION FOR PIANO PEDALS.
APPLICATION FILED FEB. 8, 1906.

Fig. 4.

Fig. 1.

Fig. 2

Fig. 3.

A technical drawing of a mechanical assembly. It features a central vertical cylinder with a flared base. A horizontal rod, labeled 'G', is attached to the side of the cylinder. A smaller vertical component, labeled 'C', is positioned within the cylinder. A horizontal rod, labeled 'D', is attached to the side of the cylinder at a lower position than 'G'. The entire assembly is shown in a cross-sectional view.

UNITED STATES PATENT OFFICE.

JOHN R. DREW, OF SAN FRANCISCO, CALIFORNIA.

ADJUSTABLE EXTENSION FOR PIANO-PEDALS.

No. 839,276.

Specification of Letters Patent.

Patented Dec. 25, 1906.

Application filed February 3, 1906. Serial No. 299,255.

To all whom it may concern:

Be it known that I, JOHN R. DREW, a citizen of the United States, residing in the city and county of San Francisco, State of California, have invented certain new and useful Improvements in Adjustable Extensions for Piano-Pedals; and I hereby declare the following to be a full, clear, and exact description of the same.

10 My invention relates to that class of attachments to piano-pedals by which an adjustable extension is provided to suit particular cases, especially for children, who having to sit high enough to enable them to 15 reach the keyboard are not able to reach the pedals with their feet.

The object of my invention is to provide a simple and effective adjustable extension for piano-pedals adapted by its construction to 20 be readily and firmly fitted to any pedal and to be easily carried about, the latter advantage making it very serviceable to music teachers.

My invention consists in the novel construction of the adjustable extension, which I shall hereinafter fully describe by reference to the accompanying drawings, in which—

Figure 1 is a side elevation of my adjustable extension. Fig. 2 is a front view of the 30 same. Fig. 3 is a cross-section on the line xx of Fig. 2 looking upwardly. Fig. 4 is a plan view of the foot-rest. Fig. 5 is a detail sectional view showing the connection of the jaws with the stock and a portion of the stem.

35 Referring to Figs. 1 and 2, A is a tubular stock having a foot-block B. C and D are the opposing jaws of a clamp, the lower portions of said jaws, as shown at c and d , being shaped to embrace the piano-pedal from each 40 side and to clasp said pedal between them. These jaws are of a springy nature and are adapted to be compressed or set up to clamp upon the pedal or to be separated in order to relieve them from the pedal by any suitable 45 means—as, for example, by the cross-bolt E, passing through the jaws, and the thumb-nut F, seated on the threaded end of said bolt. The jaws C and D of the clamp may be carried by the stock A or by its foot-block B 50 in any suitable manner; but in order to adapt the clamp to the necessities of particular cases and to insure a firm and reliable grip the best construction is that here shown—namely, one in which one of the jaws—say the 55 jaw C—is rigidly carried by the lower end of the stock, while the other jaw D is pivotally

connected therewith, so that it may be moved to an angle with the plane of the gripping-face of the jaw C.

Any suitable pivotal connection may be employed, though a practical construction is that here shown, wherein the upper end d' of the jaw D is curved inwardly and is fitted to turn upon and about the lower projecting end of the stock A, so that it is pivotally mounted 60 thereon, the end of the stock being flanged, as shown at G, against a washer g , which lies under and supports the jaw end. This movement of the jaw enables the clamp to fit those piano-pedals which have sloping or tapering 65 shanks or necks. If the jaws should present only parallel faces, it is obvious that they will not grip a tapering pedal-neck firmly; but by having one of the jaws movable, so as to turn to an angle to the plane of the face 70 of the other, they will grip such sloping necks with a long bearing and be firmly attached thereto.

H is a foot-rest which is secured upon the upper end of a stem I, which is telescoped in 80 the tubular stock A, whereby it may be raised or lowered therein. A set-screw J is adapted to hold the stem in any position to which it is adjusted. The foot-rest H is best set upon the top of the stem I at an inclination, whereby the proper and easy slope is 85 provided for the pressure of the foot.

In the collapsed condition of the device, in which the foot-rest is pushed down to its limit, it may be carried conveniently in a 90 satchel and brought out for use when required. It is readily clamped to the pedal, and then by loosening the screw J the foot-rest H may be raised to the proper point to suit the individual and there fixed. It is 95 readily disconnected from the pedal, if required, or it may be permitted to remain on the pedal without interfering with the normal use of said pedal, as it clamps it far enough back to allow the pressure of the foot 100 on the front end without inconvenience.

Having thus described my invention, what I claim as new, and desire to secure by Letters Patent, is—

1. In an adjustable extension for piano-pedals, a foot-rest, an elongated bar carried thereby and a clamping device mounted on said bar comprising opposing jaws, with means for setting and relieving them, one of said jaws being movable about the axis of the 105 bar.
2. An adjustable extension for piano-pedals,

als, comprising a stock, a clamp carried by the lower end of the stock, and consisting of a jaw fixed thereto, an opposing jaw movable about the axis of the stock, and means for setting the jaws together and relieving them, and a foot-rest carried by said stock.

3. An adjustable extension for piano-pedals, comprising a tubular stock, a clamp carried by the lower end of the stock and consisting of a jaw fixed thereto, an opposing jaw movable about the axis of the stock, and

means for setting the jaws together and relieving them, a foot-rest having a stem adjustable in said tubular stock, and means for fixing said stem where adjusted.

In witness whereof I have hereunto set my hand.

JOHN R. DREW.
